UNITED STATES PATENT OFFICE

158,663

LADY'S STOCKING

Baxter D. Huntley, Charlotte, N. C.

Application January 23, 1950, Serial No. 7,402

Term of patent 14 years

(Cl. D47—7)

To all whom it may concern:

Be it known that I, Baxter D. Huntley, a citizen of the United States of America, residing at Charlotte, in the county of Mecklenburg, State of North Carolina, have invented a new, original, and ornamental Design for a Lady's Stocking, of which the following is a specification, reference being had to the accompanying drawing, forming a part thereof.

I claim:

The ornamental design for a lady's stocking, substantially as shown and described.

BAXTER D. HUNTLEY.
